Design for Cooking Stoves.— Patented March 28, 1854.—

Sam. D. Vose.
Albany, N.Y.
March 1854

Samuel D. Vose of Albany, N.Y.
Letters Patent No. 637. Dated March 28th, 1834.

The schedule referred to in these Letters Patent, and making part of the same.

To all whom it may concern:

Be it known that I, Samuel D. Vose, of Albany, County of Albany, and State of New York, have invented or produced a new design for an ornamental cooking stove, and I do hereby declare that the following is a full and exact description of the same, reference being had to the drawings annexed to, and making part of, this specification.

The invention or design cannot be easily described in words.

References to the drawings are made by the use of the following letters, to designate the various parts of the stove:

FT	denotes	the	false	top,
UT	"	"	upper	top.
MT	"	"	middle	top.
B	"	"	bottom.	
UF	"	"	upper	front and door attached.
LF	"	"	lower	" "
US	"	"	upper	side and door attached.
LS	"	"	lower	" "
L	"	"	leg.	

I do not claim any separate figure or ornament on any of these parts. What I claim as my invention, and desire to secure by Letters Patent, is the arrangement of the several figures, and mouldings combined together the whole forming a design for an ornamental cooking stove, as herein set forth and described.
